DESIGN FOR A BASEBALL SCHEDULE CARD

Nicholas J. Pauly, Dubuque, Iowa

Application May 5, 1939, Serial No. 84,810

Term of patent 3½ years

To all whom it may concern:

Be it known that I, Nicholas J. Pauly, a citizen of the United States, residing at Dubuque, in the county of Dubuque and State of Iowa, have invented a new, original, and ornamental Design for a Baseball Schedule Card, of which the following is a specification, reference being had to the accompanying drawing, forming part thereof.

The figure is a plan view of a baseball schedule card, showing my new design, a corresponding de-

sign being shown on the reverse side of the schedule card, said card being of no substantial thickness, the features being flush with the surface. The printed matter appearing in dotted lines on the design is merely illustrative.

I claim:

The ornamental design for a baseball schedule card, as shown and described.

NICK J. PAULY.
